Primary Examiner—Mark A Goodwin*(74) Attorney, Agent, or Firm*—Amy M. Fernandez(57) **CLAIM**

The ornamental design for a multiple product package, as shown and described.

DESCRIPTION

FIG. 1 is a perspective view of the multiple product package showing our new design in closed condition.

FIG. 2 is a front elevation view of the exterior thereof.

FIG. 3 is a rear elevation view of the interior thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showings of an unclaimed product in the multiple product package, and the unclaimed periphery of this multiple product package, are for illustrative purposes only and form no part of the claimed design.
